UNITED STATES PATENT OFFICE.

JOHN ANDERSON, OF LEXINGTON, MISSOURI.

SWITCH-OPERATOR.

No. 903,825.

Specification of Letters Patent.

Patented Nov. 17, 1908.

Application filed March 28, 1908. Serial No. 423,961.

To all whom it may concern:

Be it known that I, JOHN ANDERSON, a citizen of the United States, residing at Lexington, in the county of Lafayette and State 5 of Missouri, have invented certain new and useful Improvements in Switch-Operators, of which the following is a specification.

My invention relates to improvements in switch operators; and is especially adapted 10 for operating the switches of street railways.

My object is to provide means for throwing switches open or closed, so that the motorman need not alight from his car to perform these operations.

15 A further object is to provide means for operating switches without the use of electrical appliances of any description.

In order that the invention may be fully understood, reference will now be made to 20 the accompanying drawing, in which:

Figure 1 represents a plan view of a switch provided with my improvements. Fig. 2 is a broken section of the same on line II—II of Fig. 1, with a car provided with a tripping device employed in carrying out the invention. Fig. 3 is a broken side elevation of 25 a primary lever employed in carrying out the invention.

1 designates a straight track and 2 a curved track, communicating with each other.

3 designates a switch-point which permits the car 4 to pass around the curve when said point is thrown open.

5 designates a slot which parallels one of 35 the curved rails and a portion of one of the straight rails of the tracks, as shown in Fig. 1. Said slot is made very narrow so that buggy wheels and the like cannot enter the same.

40 6 designates a trip-arm suspended beneath the car and adapted to enter slot 5 for a purpose hereinafter described. Said trip-arm is slidably secured by a pin-and-slot connection 8 to a bracket 9 depending from the un-

45 derside of the car. Arm 6 is lowered into the slot and raised therefrom by a lever 10 connected by a link 11 to a foot-lever 12, which latter is arranged conveniently to the motorman. Lever 10 is fulcrumed upon a

50 pin 13 carried by a bracket 14, depending from the underside of the car. Lever 12 is fulcrumed upon a pin 15, and when its free end is depressed to raise the trip-arm 6 from slot 5, said free end is engaged by a spring- 55 actuated latch 16 which holds said free end depressed until freed by the motorman.

17 18 designate two primary levers arranged at opposite sides of the switch-point 3 near the terminals of slot 5. The free ends of said levers intersect said slot, as shown in 60 Fig. 1. Lever 17 is fulcrumed upon a pin 19 and connected to the switch-point 3 by means of a resilient connecting-rod 20, a bell-crank lever 21, and a link 22. With this arrangement it is obvious that when the car is passing in the direction of arrow *a* arm 6 will contact with the free end of lever 17 and 65 push the same out of its path, thereby causing said lever, through the instrumentality of its connecting parts, to throw the switch-point open so that the car may enter upon 70 the curved track 2.

The free end of lever 18 is connected to the switch-point 3 by a cable 23 which passes around guide-sheaves 24, and is provided 75 with a retractile spring 25 which permits lever 18 to continue to move after the switch-point 3 has been closed. Although this cable intersects the slot near the switch-point it is arranged far enough below the end of trip-arm 6 to prevent the same from contacting therewith.

Lever 18 is provided near its free end with an upturned lug 26, which is brought into coincidence with the slot when the free end 85 of lever 18 is swung backward by the opening of the switch-point 3, hence when the car is passing around the curve, trip-arm 6 will contact with lug 26 and push the lever forward until the lug passes out of the path 90 of said trip-arm. When the lever moves forward, as above described, it will close the switch-point through the instrumentality of the cable 23.

When the switch-point is located in the 95 street of a city, levers 17 and 18 and the means connecting the same to the switch-point, are arranged in recesses 27 and 28, respectively, which may be covered with the same kind of material employed in paving 100 the street. When the apparatus is located in outlying districts, the mechanism above described, may be left uncovered and the slot 5 may be dispensed with. I also reserve the right to make such other changes as 105 properly fall within the scope of the appended claims.

Having thus described my invention, what I claim is:—

1. In combination with a straight and a 110 curved track, with a slot formed in the road-bed along a part of said tracks, a switch

point, a lever pivoted intermediate its ends so as to have one of its ends project in said slot, a bell crank lever connected to said switch point, a resilient connecting rod between said bell crank lever and the inner end of said first named lever, a second pivoted lever having its free end extending across said slot at a point along the curved track, a flexible connection between the outer 10 end of said second lever and said switch point, and an upturned lug on said second lever designed when said switch point is in open position to enter said slot, and when said switch point is in closed position to 15 move out of said slot.

2. In combination with a straight and a curved track, a switch point, a pair of primary levers on opposite sides of the switch point to operate the latter, lever engaging means on the car, and an element carried by one of said levers designed in one position of said switch point to be engaged by said throwing means, and in another position of the switch point to be out of alignment with said throwing means.

3. In combination with a straight and a curved track, and a switch point, a pair of horizontal levers pivoted on opposite sides of said switch point, one extending across 20 the straight track and the other across the curved track, means connecting the inner end of one of the levers with one side of the switch point, and means connecting the outer 25 end of the other lever with the other side of the switch point, lever engaging means on

the car, and a vertical part adjacent the free end of said second lever designed in one position to engage said car lever engaging means and in a second position to be out of alignment therewith.

4. In combination with a straight and a curved track and a switch point, a pair of horizontal levers on opposite sides of said switch point, a bell crank lever connected to one side of said switch point, a resilient connection between said bell crank and the inner end of one of said levers, a flexible connection between the outer end of the other of said levers and the opposite side of said switch point, and guiding means for said 45 50 flexible connection.

5. In combination with a straight and a curved track, a switch point, a lever pivoted intermediate its ends so as to have one of its ends project beyond the straight track, a bell crank lever connected to said switch point, a resilient connecting rod between said bell crank lever and the inner end of said first named lever, a second pivoted lever having its free end extending beyond the 55 60 curved track, a flexible connection between the outer end of said second lever and said switch point, and an upturned lug on said second lever.

In testimony whereof I affix my signature, 65 in the presence of two witnesses.

JOHN ANDERSON.
